MEANS FOR PREVENTING LEAKAGE AROUND STAY WIRES OF CONCRETE WALLS

Filed Nov. 20, 1926

FIG. 1.

Inventor

Charles A. Luck.

By. Owen & Owen,

Attorneys

UNITED STATES PATENT OFFICE.

CHARLES A. LUCK, OF DETROIT, MICHIGAN.

MEANS FOR PREVENTING LEAKAGE AROUND STAY WIRES OF CONCRETE WALLS.

Application filed November 20, 1926. Serial No. 149,556.

This invention relates to concrete work, and particularly to a method of treatment of concrete walls or the like at the exposed ends of stay or reinforcing wires or rods 5 to prevent leakage through the wall around the wires or rods, and also to a device for use in connection with and to facilitate such treatment.

In masonry work the form boards for concrete walls or the like are customarily tied together in spaced relation by cross wires which extend through the wall when formed and extend from the sides thereof through the form boards and around outside braces. 10 When the forms are removed, the tie wires are usually cut off close to the wall, and unless the exposed ends of these wires are sealed with respect to the wall, leakage occurs through the wall around the wires, and 15 this tendency to leak is increased by the rusting and consequent reducing in size of the wires.

To prevent such leakage, it has been customary, after the forming of a wall and removal of the forms, to chip away the concrete to provide a pocket or recess in the wall surface around the exposed end of the wire, and after cutting the wire end off or turning it back within the pocket, to then fill 20 the pocket with a sealing cement flush with the wall side to prevent leakage.

This is a tedious, expensive and uncertain method of preventing such leakage, inasmuch as it is very difficult and takes considerable time, especially when extremely hard water-proof cement is used, to chip out the cement to form the pockets, and in view of this difficulty workmen are very apt to make 25 the pockets so shallow that an effective sealing cannot be obtained, and this cannot be determined from an inspection of the work after it is completed. It also frequently happens that the workmen will miss some of the wire ends.

The object of this invention is the provision of a method, and means for carrying it out, for sealing the exposed wire ends of concrete work in a manner which is easy, simple, inexpensive and efficient, and which 30 obviates the objections and difficulties incident to the methods heretofore employed.

The invention is fully described in the

following specification and an embodiment of the same illustrated in the accompanying drawings, in which,—

Figure 1 is a top view of a concrete wall with the form boards in place and with a portion broken away to show pocket forming means embedded in the side surfaces of the wall in encircling relation to respective 55 tie wires. Fig. 2 is an enlarged fragmentary section of Fig. 1 taken centrally through the pocket forming member longitudinally of the associated tie wire. Fig. 3 is a fragmentary section of the wall similar to Fig. 60 2 with the form boards removed, the associated end of the tie wire turned back within the pocket, and the pocket filled with cement. Fig. 4 is a perspective outer end view of a 65 pocket forming member embodying the invention with a tie wire extending therethrough, and Fig. 5 is a similar view of the pocket forming member in the act of being engaged with a tie wire.

Referring to the drawings, 1 designates a 70 concrete wall, 2 the form boards at opposite sides thereof, 3 the stay-boards or members at the outside of the form boards, and 4 the tie wires, which extend through the wall, or the space between the form boards, and 75 tie the form boards together in proper relation, as well understood in the art. These tie wires are usually of continuous loop or endless form with their outer end portions looped over the stay members 3 and their 80 cross runs extending through holes in the form boards and twisted together between the form boards to effect a desired tightening of the form boards against interposed strut or spreader members 5.

Preparatory to depositing the cement in the form, pocket forming members 6 are secured to the inner sides of the form boards around the respective stay wires so that when the concrete is poured a pocket is 85 formed in the side surface of the wall around each stay wire at its point of emergence from the wall.

A simple and efficient form of member for this purpose is illustrated in the drawings 90 and consists of a substantially conical shaped member with one side closed along a line substantially parallel to the axis of the cone. The member has a centrally disposed open-

ing 7 at its apex portion through which the wire 4 extends, and in order to enable the member 6 to be placed in engagement with a wire the member is split, as shown at 8, 5 along the side thereof, which is substantially parallel to its axis and with the split extending from the opening 7 to the outer edge of the member. One edge wall of the member 6 at the split 8 is provided with an inwardly turned flange 9, the outer end of which, or that disposed at the large end of the cone member, being projected beyond the member and sharpened to form a brad 10 for driving or forcing into the inner side of 10 an associated form board to hold the member 6 in fixed relation thereto. The brad 10 is of flat form and is preferably forced into a board with the flatness thereof parallel with the grain of the board. An ear 11 is provided on the outer edge of the member 6 substantially diametrically opposite the brad 10 and extends from the member in the plane of the outer end of such member so as to lie flat against a form board. This ear is 15 perforated to facilitate the driving of a nail or tack 12 therethrough and into the board to assist the brad 10 in holding the member 6 to the board.

It is apparent that when the pocket forming member 6 is in position on a form board, its outer or large end bears flat against the board so as to exclude any concrete from entering the member, and the wire 4 extends therethrough free from contact with either side of the member, except possibly at the point where it passes through the opening 7. By making the member 6 in the form shown, that is, with one side substantially at right angles to the surface of 20 the board against which it is to be secured and with its opposite side at an inclined angle thereto, it is adapted to accommodate the particular angle of the associated portion of a tie wire 4 with which it is engaged.

When the form is removed from the concrete the wires 4 are cut without the form boards to permit them to be drawn through the boards. If the pocket forming members 6 do not withdraw from the concrete with 25 the boards, they may be easily removed from the concrete by gripping the flange 9 with a pair of pliers and then applying a twisting strain to the flange so as to tend to contract the size of the member to permit it to be easily withdrawn from the wall. This contraction of the member is made possible by reason of the slotted form of the same.

When the members 6 have been removed from the wall the exposed ends of the wires 4 are either cut off within the pockets or turned back therein, as shown in Fig. 3, and the pocket then filled with concrete or a suitable sealing material. By turning the wire back within the pocket it provides an anchorage for the sealing material.

Having thus described my invention, what I claim as new and desire to secure by Letters Patent is:

1. A pocket forming member of the class described, being substantially conical in form with its outer end open and having a small wire receiving opening at its apex portion, one side of the member being substantially parallel with its axis.

2. A pocket forming member of the class described, being substantially conical in form with one side substantially parallel with its axis and split throughout its length, the split terminating at its inner end in a wire receiving opening.

3. A pocket forming member of the class described, formed of flexible material and having a relatively large open outer end adapted to bear substantially flat against a form board, the member being gradually reduced in size from its outer to its inner end and having a small wire receiving opening at its inner end and also having a slit extending outwardly along one side thereof from said inner opening to its outer opening to permit a contraction or expansion of the member.

4. A pocket forming member of the class described, formed of flexible material and having a relatively large open outer end adapted to bear substantially flat against the form board, the member being gradually reduced in size from its outer to its inner end and having a small wire receiving opening at its inner end and also having a slit extending outwardly along one side thereof from said inner opening to its outer opening to permit a contraction or expansion of the member, one wall of said slit having an inwardly turned flange the outer end of which terminates without the outer end of the member and forms a form board engaging brad.

5. The combination with the tie wire of a form for concrete walls, of a pocket-forming member encircling an end portion of the wire and adapted to project into a surface of the wall when formed, said member having a relatively large outer open end and a reduced inner end with an opening therein through which the wire passes.

6. In combination with the form boards and tie wires for a concrete wall, of a tapered pocket-forming member encircling the tie wire and having a relatively large outer open end and a reduced inner end with an opening therein through which the wire passes and having provision at its outer end for attaching to a form board, said member being of less length than the thickness of the wall to be formed and being removable from the wall after it has set to form a surface pocket therein around the respective end of the tie wire.

7. The combination with the form boards

and tie wires of a concrete wall form, of tapered members attached to the inner sides of the form boards in encircling relation to the adjacent ends of the tie wires, said members having large openings at their outer ends relative to the wall and small openings at their inner ends for the passage of the wires and being slit at a side thereof from

one opening to the other, said members being removable from the wall after it is formed ¹⁰ to form surface pockets therein around the adjacent ends of the tie wires.

In testimony whereof I have hereunto signed my name to this specification.

CHARLES A. LUCK.
